(57) **CLAIM**

I claim the ornamental design for an oval candle jar, as
shown and described.

DESCRIPTION

FIG. 1 is a perspective view of the oval candle jar according
to the present invention;

FIG. 2 is a front elevational view of the oval candle with a
section broken away for clarity of illustration;

FIG. 3 is an end elevational view of the oval candle with a
section broken away for clarity of illustration;

FIG. 4 is a top view of the oval candle jar depicted in FIG.
1; and,

FIG. 5 is a bottom view of the oval candle jar depicted in
FIG. 1.
